W. W. Womack

ATTORNEY

UNITED STATES PATENT OFFICE.

EDGAR M. BENHAM, OF NORWOOD, OHIO, ASSIGNOR TO THE MOSLER LOCK COMPANY,
OF COVINGTON, KENTUCKY, A CORPORATION OF OHIO.

KEY.

Application filed March 10, 1924. Serial No. 698,057.

To all whom it may concern:

Be it known that I, EDGAR M. BENHAM, a citizen of the United States, residing at Norwood, in the county of Hamilton and State 5 of Ohio, have invented certain new and useful Improvements in Keys, of which the following is a specification.

This invention relates to keys, and more particularly relates to keys which have removable number plates, whereby each key 10 is identified by a number and the number may be changed by removing the number plate and substituting another plate having a different number.

15 The principal object of my invention is to provide a key having a removable and replaceable number plate, and a key in which such number plate is normally held in position firmly and securely. A further object 20 of my invention is to provide a key of the above character which is simple and durable in construction and attractive in appearance. Other objects of my invention will be in part obvious and in part pointed out hereinafter.

25 In order that a clearer understanding of my invention may be had, attention is hereby directed to the accompanying drawings forming a part of this application and illustrating one embodiment of my invention.

30 Referring to the drawings, Fig. 1 is a side elevation of the key with the number plate in position thereon; Fig. 2 is a sectional view taken on the line 2—2 of Fig. 1; Fig. 3 is a side elevation of the head portion of 35 the key with the number plate removed; and Fig. 4 is a side elevation of the number plate. Similar reference characters refer to similar parts throughout the several views of the drawings.

40 Referring to the drawings, there is shown a key 1 having a head 2 and a number plate 3 removably secured to the head 2 by means of a small screw 4, such as a watch screw. The head 2 has a hole 5 and the number

45 plate 3 has a hole 6 aligning with the hole 5 to accommodate the key for being secured to a key ring or hung from a nail or hook or the like.

The head 2 is provided on one side with a recess 7 which is bounded by a flange 8, 50 and the number plate 3 is adapted to be received in this recess 7, where it may be held by means of the screw 4, which extends through a suitable hole 9 in the head 2 and into engagement with a threaded hole 10 in 55 the number plate 3. Preferably, the thickness of the number plate 3 is such that when it is seated in the recess, its outer surface will be flush with the flange 8 of the head. The recess 7 and number plate 3 may be 60 made in various different corresponding shapes. As illustrated, recess 7 and the number plate 3 are circular.

In a key of the character described, a number plate may easily be removed and a new 65 one substituted by unscrewing the screw 4 from the plate to be removed, and by engaging this screw with another plate placed in the recess 7.

Instead of, as shown, conditioning the key 70 portion which comprises the head for the association therewith of a removable number plate, other portions of the key may be so conditioned.

75 As many changes could be made in the above construction and as many apparently widely different embodiments of this invention could be made without departing from the scope thereof, it is intended that all matter contained in the above description or 80 shown in the accompanying drawings shall be interpreted as illustrative and not in a limiting sense.

What I claim is:—

85 A key of the character described and having a head, a recess on one side of the head, and a flange about said recess, a separate number plate shaped to fit in said recess flush with said flange, and a screw for removably securing said plate in said recess, the head 90 of the key and said plate having aligned perforations.

This specification signed this 4th day of March, 1924.

EDGAR M. BENHAM.
